REGENERATIVE FURNACE

Otto Reiner, Rheinhausen/Niederrhein, Germany

Application September 28, 1936, Serial No. 103,023
In Germany October 2, 1935

10 Claims.

(Cl. 277—6)

My invention relates to regenerative furnaces and more particularly to an apparatus by which the flows of heating and waste gases are reversed, that is to say, the chambers of the furnace are alternately connected to a supply of heating gas, and to a flue for the discharge of the waste gas.

It is an object of my invention to provide an improved apparatus which reverses the gas flows without loss of gas and without rise of pressure in the gas supply pipe while reversing, and does not interrupt the supply of gas, so that the operation of the furnace is continuous.

To this end, in a regenerative furnace which is equipped with the usual regenerator chambers and with suitable ducts for supplying gas to the chambers, I provide a reversing apparatus which comprises a pair of controls each connected to one of the regenerator chambers and to the waste gas flue, and a reversing valve whose casing is connected to both controls. Each control has a pair of controlling valves for alternately connecting the regenerator chamber with which it is associated, to the casing of the reversing valve and to the waste gas flue. I further provide a timing mechanism which is actuated by a motor, or any other suitable source of power, and parts, such as a drum and cables, for connecting the timing mechanism to the valves in each control, so that the controls are operated in sequence. The timing mechanism has a pair of arms, or any other suitable members, one on the shaft of the cable drum and the other on the shaft of the reversing valve, for throwing over this valve and regulating the admission of heating gas to the regenerator chambers in timed relation with the operation of the controls.

By providing a reversing apparatus as described, lowering of the temperature at the front end of the furnace during reversing is avoided, the metal output of the furnace per unit of time is increased, and its performance becomes steady and continuous. Besides, the apparatus is quite gastight.

In the accompanying drawings I have illustrated, by way of example, a regenerative furnace equipped with a reversing apparatus according to my invention.

In the drawings:

Fig. 1 is a partly sectional elevation of the furnace and the reversing apparatus showing that position of the controlling and reversing valves in which the regenerator chamber at the right is connected to the waste gas flue, and the chamber at the left to the supply of heating gas.

Fig. 2 shows an intermediate position in which

the connection of the chamber at the right and the waste gas flue is broken but the chamber at the left is still connected to the gas supply.

Fig. 3 shows another intermediate position in which the chamber at the right has been connected to the gas supply but the chamber at the left is still disconnected from the waste gas flue, and

Fig. 4 shows the position after the reversing operation has been completed.

Referring now to the drawings, and first to Fig. 1, it will appear that my apparatus is of the type in which two controls, 5 and 6, are provided, each with a pair of controlling valves which move in opposite directions. By these means, the ducts 15 which extend from each regenerator chamber, 1 and 2, to the corresponding control, are alternately connected to a supply pipe 3 for heating gas, and to a waste gas flue 4.

Intermediate the supply pipe 3 and the two controls 5 and 6, I arrange the casing 3' of a reversing or butterfly valve 41 for reversing the flow of the heating gas, and on the casing 3' I provide a timing mechanism for operating the two controls 5 and 6 in such manner that first the valves of one control, say, the control 5, are so positioned as to break the connection of the corresponding regenerator chamber 1 to the waste gas flue 4 through the casing of the control, and to connect the chamber to the gas supply pipe 3 through the casing 11 of the control 5 and the casing 3' of the reversing valve 41. The timing mechanism is now operated and, through the medium of two arms 38 and 45, as will be described in full detail below, abruptly throws over the reversing valve 41 and then actuates the valves of the other control 6 to break the connection of chamber 2, at the left, to the casing 3' of the reversing valve 41 and to connect that chamber to the waste gas flue 4 through the casing 11' of control 6.

Preferably, the timing mechanism is so designed that the controlling valves of the controls 5 and 6 are operated by a cable drum 25 which is alternately turned through an angle of 180 degs. in opposite directions. When the drum is turned in a given direction, and has almost completed its movement, it raises the lower controlling valve, as shown for the lower valve 8 of control 5, making the connection of chamber 1 and flue 4, while at the same time the upper valve 7 is lowered, being connected to the lower valve by cables, as will be described, and breaks the connection of chamber 1 and the casing 3' of the reversing valve 41. The drum performs the same

function with respect to the valves in the other control 6 when turning in the opposite direction. Before operating the controls, the drum, through arms 38 and 45, throws over the reversing valve 41.

The timing mechanism requires only a single reversible motor for actuating the drum 25. Preferably, a manually operated drive 48 is provided as a stand-by in case the motor 26 should fail. It will appear that the timing mechanism is very simple.

Each control, as mentioned, comprises a pair of superimposed controlling valves connected for movement in opposite directions. The valves are hollow and equipped with means for circulating a cooling liquid, normally water, in their interiors. Each valve cooperates with a liquid seal in the casing of its control and an annular float is arranged in each seal for closing the seal against the casing. The valve has a projection projecting on its lower face by which it depresses the float when being lowered by the drum 25. If desired, springs may be provided for assisting the upward movement of the floats. The valve rods are hollow and house the circulating pipes for the cooling water.

By designing the controlling valves as described, neither the heating gas nor the waste gas has access to the water in the valves and in the seals and the water is not contaminated by impurities from such gases. This arrangement also prevents the vapor from the liquid from being entrained by the heating gas.

The apparatus will now be described in full detail. The regenerator chambers 1 and 2 of the furnace have already been referred to. 18 is a duct connecting the chamber 1 to the corresponding control casing, and 19 is a similar duct for the chamber 2 and its control casing. The lower end 40 of the control 5 is connected to the flue 4 by a duct 20, and a similar duct 21 is arranged for the control 6. It will appear that the casings of the two controls 5 and 6 are arranged intermediate the regenerator chambers 1 and 2, the heating gas supply pipe 3, and the flue 4. The supply pipe 3 is attached to the lower end of the reversing valve casing 3' and both ends of the casing 3' are connected to the controls 5 and 6 by suitable pipes.

The control 5 will now be described, it being understood that the control 6 is quite similar. Corresponding parts in both controls are designated by the same reference numerals, the parts of control 6 being distinguished by the index "6". A lower valve 8 and an upper valve 7 are mounted to reciprocate vertically in the casing 11 of the control 5. Both valves are hollow for the reception of cooling water, and are equipped with downwardly projecting projections 9 and 10, respectively. 12 is a liquid seal in the wall of the casing 11 for cooperation with the upper valve 7, and 13 is a similar seal for the lower valve 8. The seals may be provided with means, not shown, for supplying and circulating the water with which they are filled. The seals 12 and 13 are equipped with floats 14 and 15, respectively, which are annular and adapted to be engaged and depressed by the projections 9 and 10 of the corresponding valves. When a valve is raised beyond its seal, as shown for the lower valve 8, the float is released and held against a shoulder 17 which is formed on the inner side of casing 11 above the seal 13, a similar shoulder 18 being disposed above the seal 12.

It will appear that the gas supply pipe 3 is

connected to the upper ends of the casings 11 and 11' through the reversing valve casing 3' and suitable pipes opening into the control casings above the seals 12 and 12'. The lower end of each casing is connected to the corresponding regenerator chamber 1 or 2 by the above mentioned ducts 18 or 19 which opens above the lower seal 13, or 13', and the seal surrounds the upper end of the duct 20 or 21 which is connected to the flue 4 at its lower end.

The lower valve 8 is equipped with a tubular valve rod 22 on whose upper end an adjustable weight 23 is placed. A cable 24 connects this rod to the drum 25, being supported by a pair of pulleys 31a at the upper end of a pair of uprights 30 on the top of casing 11. Another cable 27 on pulleys 31a' at the upper end of uprights 30' connects the drum 25 to the upper end of valve rod 22' in control 6. The motor 26 which, as mentioned, is reversible and at each operation imparts to the drum 25 a turning movement through 180 degs., is connected to the drum 25 by a reduction gearing 25a, 25b.

The upper valve 7 is also equipped with a tubular valve rod 28 which surrounds the rod 22 in co-axial and spaced relation. 28 are cables supported by pulleys 31 and connected to the upper ends of the two valve rods so that the valves are caused to move in opposite directions, the valve 7 being raised when the valve 8 descends, and vice versa. 32 is a sleeve secured to the uprights 30 for guiding the valve rod 28 which in turn guides the inner valve rod 22. 33 is a supply pipe, and 34 is a discharge pipe for the cooling liquid circulating in the lower valve 8, both pipes being inserted in the tubular rod 22 of that valve. The lower ends of the two pipes open into the interior of the valve. A similar arrangement, with pipes 35 and 36 for the supply and discharge of the liquid, is provided in the outer valve rod 28 of the upper valve 7, the lower ends of the pipes opening into the interior of that valve.

37 is the shaft of cable drum 25, and 38 is an arm on the shaft, as mentioned. 42 is the shaft 45 of the reversing valve 41 mounted in the casing 3', and on it is mounted the arm 45. The reversing valve has two final positions in which it engages the seats 43 and 43', as shown in Fig. 1, or the seats 44 and 44' which are formed on the inner side of casing 3'. The arm 38 of the timing mechanism which is provided with means such as screws 38' for regulating its effective length, has a pin 40 at its free end for engaging a slotted member 46 at the free end of arm 45. Screws 45' are arranged for regulating the effective length of this arm 45. The arms move in the same vertical plane and the pin enters the slotted member when the timing arm 38 has been moved far enough in the direction of arrow 49.

It is understood that instead of a motor 26 which is connected to a switch 26a on a platform 47, any other suitable actuating means for the timing mechanism might be provided. Preferably, a manually operated mechanism 48, with suitable gearings, sprockets and chains, is arranged on the platform 47 and connected to the drum 25 in case the motor should fail.

The operation of my novel reversing apparatus will now be described. In the position of the controlling and reversing valves illustrated in Fig. 1, the valve 8 of the control 5 has been lifted from its seal 13 and the regenerator chamber 1 is open toward the duct 21 and the flue 4. The waste gas flows from chamber 1, as indicated 75

by the arrow. The upper valve 7 is in its seal 12, breaking the connection of the upper and lower portions of casing 11. The float 14 in the seal 12 is engaged by the projection 9 of valve 7 and forced down into the seal. The float 15 of the lower seat 13 is held against the shoulder 17 by the lift of the liquid.

The regenerator chamber 2 is connected to the supply pipe 3 through control 6. The controlling valves 1' and 8' are at opposite ends of the casing 11', the lower valve 8' being in its seal 13', and the upper valve 1' being off its seal 12' and supported in its elevated position by cables 29'. The cable 24 which, as described, connects the drum 25 of the timing mechanism to the valve rod 22 of the lower valve 8 in the casing 11 of control 5, is taut under the pull of weight 23, while the cable 27 which has a similar function with respect to the rod 22' of valve 8' in the control 6, is slack. Heating gas now flows to chamber 2 through pipe 3, reversing valve casing 3' and control casing 11', as indicated by the arrow.

When it is desired to reverse the furnace, the motor 26 of the timing mechanism is cut in to turn the timing arm 38 in the direction of arrow 49. During the first part of the rotation of drum 25 through 180 degs., it unwinds the cable 24 and the lower valve 8 descends upon its seal 13, Fig. 2, assisted by the weight 23 with which its rod 22 is loaded. The connection between chamber 1 and flue 4 is now broken. At the same time, the upper valve 7 is elevated by cables 29 and the chamber 1 is now connected to the reversing valve casing 3'. However, the reversing valve 41 has not yet been thrown over so that for the present the supply of gas to the chamber 1 is cut off.

During the movement of drum 25 from the position in Fig. 1 to that in Fig. 2, the valves 1' and 8' of the control 6 remain in their positions, since only a portion of the slack of cable 27 has been taken up by the drum. The supply of heating gas to chamber 2 is therefore continued.

Upon still further movement of drum 25 and its arm 38 in the direction of arrow 49, the pin 40 of the timing arm enters the slotted member 46 of the valve arm 45 and the reversing valve 41 is thrown over while the drum 25 turns from the position in Fig. 2 into that in Fig. 3. This is a short period, and so the reversing valve is thrown over abruptly. Cable 24 has now become slack, and so the controlling valves in the control 5 remain in their positions and gas is admitted to chamber 1 while the chamber 2 is cut off from the supply of gas but not yet connected to the waste gas flue 4. However, the cable 27 is under tension when the arms 38 and 45 have become engaged.

In the final position, Fig. 4, the timing arm 38 has disengaged the valve arm 45 and the position of the reversing valve is not influenced by the further movement of drum 25. However, the valves in the control 6 are now operated by cable 27, the valve 8' being elevated while the upper valve 1' is lowered into its seal 12' by cables 29'. The chamber 2 is now disconnected from the supply of heating gas and connected to the flue 4 while the other chamber 1 is supplied with heating gas, as indicated by the arrows in Fig. 4.

The partial rotation of drum 25 through 180 degs. is performed in a comparatively short time so that the furnace is soon ready for operation in reversed condition.

When it is desired to again reverse the furnace, i. e., to return the parts into the position of Fig. 1, the motor 26 is reversed and turns the

drum 25 and the timing arm 38 backwards in the direction of arrow 50, Fig. 4. The operations which have been described will now be performed in reverse sequence, the control 6 being operated first, whereupon the reversing valve 41 is thrown over and finally the control 5 is operated to return its controlling valves into the positions illustrated in Fig. 1.

I claim:

1. In a regenerative furnace, regenerator chambers, means for supplying heating gas to, and exhausting waste gas from, said regenerator chambers, a reversing apparatus comprising a pair of controls each connected to one of said regenerator chambers and to said exhausting means, a reversing valve connected to both controls and to said supplying means, a pair of controlling valves in each control for alternately connecting the corresponding regenerator chamber to said reversing valve and to said exhausting means, a timing mechanism, means for actuating the mechanism, means for operatively connecting the mechanism to the valves of each control for operating the controls in sequence, and means operatively connected to the mechanism for throwing over said reversing valve and regulating the admission of heating gas to said regenerator chambers in time with the operation of said controls.

2. In a regenerative furnace, regenerator chambers, means for supply heating gas to, and exhausting waste gas from, said regenerator chambers, a reversing apparatus comprising a pair of controls each connected to one of said regenerator chambers and to said exhausting means, a reversing valve connected to both controls and to said supplying means, a pair of controlling valves in each control for alternately connecting the corresponding regenerator chamber to said reversing valve and to said exhausting means, a timing mechanism, means for actuating the mechanism, means for operatively connecting the mechanism to the valves of each control for operating the controls in sequence, and means operatively connected to the mechanism for abruptly throwing over said reversing valve and regulating the admission of heating gas to said regenerator chambers in timed relation with the operation of said controls.

3. In a regenerative furnace, regenerator chambers, means for supplying heating gas to, and exhausting waste gas from, said regenerator chambers, a reversing apparatus comprising a pair of controls each connected to one of said regenerator chambers and to said exhausting means, a reversing valve connected to both controls and to said supplying means, a pair of controlling valves in each control for alternately connecting the corresponding regenerator chamber to said reversing valve and to said exhausting means, means connecting the controlling valves in each control for movement in opposite directions, a timing mechanism, means for actuating the mechanism, means for operatively connecting the mechanism to the valves of each control for operating the controls in sequence, and means operatively connected to the mechanism for throwing over said reversing valve and regulating the admission of heating gas to said regenerator chambers in timed relation with the operation of said controls.

4. In a regenerative furnace, regenerator chambers, means for supplying heating gas to, and exhausting waste gas from, said regenerator chambers, a reversing apparatus comprising a pair of controls each connected to one of said

- regenerator chambers and to said exhausting means, a reversing valve connected to both controls and to said supplying means, a pair of controlling valves in each control for alternately connecting the corresponding regenerator chamber to said reversing valve and to said exhausting means, means connecting the controlling valves in each control for movement in opposite directions, a timing mechanism, means for actuating the mechanism, means for reversing the mechanism, a cable drum operatively connected to the mechanism, a cable for each control connecting said drum to one of the valves in each control, for operating the controls in sequence, and means operatively connected to the mechanism for throwing over said reversing valve and regulating the admission of heating gas to said regenerator chambers in timed relation with the operation of said controls.
5. In a regenerative furnace, regenerator chambers, means for supplying heating gas to, and exhausting waste gas from, said regenerator chambers, a reversing apparatus comprising a pair of controls each connected to one of said regenerator chambers and to said exhausting means, a reversing valve connected to both controls and to said supplying means, a pair of controlling valves in each control for alternately connecting the corresponding regenerator chamber to said reversing valve and to said exhausting means, a timing mechanism, means for actuating the mechanism, means for operatively connecting the mechanism to the valves of each control for operating the controls in sequence, an arm operatively connected to said reversing valve, another arm operatively connected to the timing mechanism, and means for temporarily connecting said arms so as to throw over said reversing valve in timed relation with the operation of said controls, for regulating the admission of heating gas to said regenerator chambers.
6. In a regenerative furnace, regenerator chambers, means for supplying heating gas to, and exhausting waste gas from, said regenerator chambers, a reversing apparatus comprising a pair of controls each connected to one of said regenerator chambers and to said exhausting means, a reversing valve connected to both controls and to said supplying means, a pair of controlling valves in each control for alternately connecting the corresponding regenerator chamber to said reversing valve and to said exhausting means, a timing mechanism, means for actuating the mechanism, means for operatively connecting the mechanism to the valves of each control for operating the controls in sequence, an arm operatively connected to said reversing valve, a slotted member on this arm, another arm operatively connected to the timing mechanism, a pin on the second mentioned arm for temporarily engaging in the slotted member on the first-mentioned arm, so as to throw over said reversing valve in timed relation with the operation of said controls, for regulating the admission of heating gas to said regenerator chambers.
7. In a regenerative furnace, regenerator chambers, means for supplying heating gas to, and exhausting waste gas from, said regenerator chambers, a reversing apparatus comprising a pair of controls each connected to one of said regenerator chambers and to said exhausting means, a reversing valve connected to both controls and to said supplying means, a pair of controlling valves in each control for alternately connecting the corresponding regenerator chamber to said reversing valve and to said exhausting means, a timing mechanism, means for actuating the mechanism, means for operatively connecting the mechanism to the valves of each control for operating the controls in sequence, and means operatively connected to the mechanism for throwing over said reversing valve and regulating the admission of heating gas to said regenerator chambers in timed relation with the operation of said controls.
8. In a regenerative furnace, regenerator chambers, means for supplying heating gas to, and exhausting waste gas from, said regenerator chambers, a reversing apparatus comprising a pair of controls each connected to one of said regenerator chambers and to said exhausting means, a reversing valve connected to both controls and to said supplying means, a pair of controlling valves in each control for alternately connecting the corresponding regenerator chamber to said reversing valve and to said exhausting means, a casing forming part of each control and housing its controlling valves, a liquid seal for each controlling valve in the casing, an annular float arranged in each seal so as to be engaged and depressed by the corresponding control valve as the valve descends into the liquid of the seal, a shoulder above each seal which is adapted to arrest the float when the float is clear of its valve, a timing mechanism, means for actuating the mechanism, means for operatively connecting the mechanism to the valves of each control for operating the controls in sequence, and means operatively connected to the mechanism for throwing over said reversing valve and regulating the admission of heating gas to said regenerator chambers in timed relation with the operation of said controls.
9. In a regenerative furnace, regenerator chambers, means for supplying heating gas to, and exhausting waste gas from, said regenerator chambers, a reversing apparatus comprising a pair of controls each connected to one of said regenerator chambers and to said exhausting means, a reversing valve connected to both controls and to said supplying means, an upper and a lower controlling valve in each control for alternately connecting the corresponding regenerator chamber to said reversing valve and to said exhausting means, a valve rod connected to the lower valve, a tubular valve rod connected to the upper valve and surrounding the rod of the lower valve, cables connecting the two rods for movement of the valves in opposite directions, a timing mechanism, means for actuating the mechanism, means for operatively connecting the mechanism to the rod of the lower valve in each control for operating the controls in sequence, and means operatively connected to the mechanism for throwing over said reversing valve and regulating the admission of heating gas to said regenerator chambers in timed relation with the operation of said controls.
10. In a regenerative furnace, regenerator chambers, means for supplying heating gas to, and exhausting waste gas from, said regenerator chambers, a reversing apparatus comprising a

pair of controls each connected to one of said regenerator chambers and to said exhausting means, a reversing valve connected to both controls and to said supplying means, a hollow upper and a hollow lower controlling valve in each control for alternately connecting the corresponding regenerator chamber to said reversing valve and to said exhausting means, a tubular valve rod connected to the lower valve, a weight on the valve rod, pipes in the valve rod for circulating cooling liquid in the interior of the lower valve, a tubular valve rod connected to the upper valve and surrounding the rod of the lower valve, pipes in the rod of the upper valve for circulating cooling liquid in the interior of the upper valve, a timing mechanism, means for actuating the

mechanism, means for reversing the mechanism, a cable drum operatively connected to the mechanism, a cable for each control connecting said drum to the valve rod of the lower valve in each control, for operating the controls in sequence, a pulley in each control, a cable supported by the pulley and connecting the rods of the upper and lower valves in the control so that the valves move in opposite directions, and means operatively connected to the timing mechanism for throwing over said reversing valve and regulating the admission of heating gas to said regenerator chambers in timed relation with the operation of said controls. 5 10

OTTO REINER. 15
